UNITED STATES PATENT OFFICE.

LLEWELLYN E. JONES, JOHN W. BREAKEY, AND WILLIAM F. CASEY, OF PHILADELPHIA, PENNSYLVANIA.

SPEED-CONTROLLING APPARATUS FOR MOTOR-CARS.

1,186,204.

Specification of Letters Patent.

Patented June 6, 1916.

Application filed January 20, 1914. Serial No. 813,300.

To all whom it may concern:

Be it known that we, LLEWELLYN E. JONES, JOHN W. BREAKEY, and WILLIAM F. CASEY, citizens of the United States, residing at Philadelphia, in the county of Philadelphia and State of Pennsylvania, have invented new and useful Improvements in Speed-Controlling Apparatus for Motor-Cars, of which the following is a specification.

This invention relates to improvements in speed controlling apparatus for motor cars and has particular application to an apparatus for cutting down the speed of a railroad and the train of cars hauled thereby in the event of such locomotive passing a caution signal above a predetermined speed.

In carrying out the present invention, it is our purpose to provide an apparatus of the class described whereby the speed of a railway car or train will be automatically cut down in the event of such car or train passing a caution signal above a prescribed speed and whereby the engineer will be automatically advised immediately that the apparatus is brought into service.

It is also our purpose to provide a speed controlling apparatus whereby the pressure in the brake pipe or train line air pipe will be automatically reduced to effect an application of the brakes to the wheels in the event of the car or train passing a road signal set at caution and wherein communication between the train line air pipe or brake pipe and the main air reservoir or other source of supply will be automatically cut off when the pressure in the train pipe is reduced so as to prevent recharging of the train line, incident to the engineer manipulating the brake valve, during the reduction of the pressure in the train line or brake pipe.

Furthermore, we aim to provide an apparatus of the type set forth which will be capable of a wide range of adjustment so that the apparatus may be installed in cars having different caution speeds.

A further object of the invention is the provision of a speed controlling apparatus for railway motor cars which will embrace the desired features of simplicity, efficiency and reliability, one which will operate under all weather conditions and one which

may be installed and maintained at a minimum expense.

With the above and other objects in view, the invention consists in the construction, combination and arrangement of parts hereinafter set forth in and falling within the scope of the claims.

In the accompanying drawings: Figure 1 is a longitudinal sectional view through a speed controlling apparatus constructed in accordance with the present invention, parts 65 being shown in elevation. Fig. 2 is a diagrammatic view of the same. Fig. 3 is a vertical sectional view on the line 3—3 of Fig. 1. Fig. 4 is a vertical sectional view through the governor showing the same in active position. Fig. 5 is a longitudinal sectional view through the main valve showing the same in closed position. Fig. 6 is a sectional view on the line 6—6 of Fig. 1, and Fig. 7 is a horizontal sectional view on the line 7—7 of Fig. 4.

Referring now to the accompanying drawings in detail, 1 indicates the brake pipe or train line air pipe of the brake system of a motor car or train, such pipe being connected up with a suitable source of air supply as the main air reservoir of the air brake system. Located in the brake pipe adjacent to the connection between such pipe and the source of air supply is a valve 80 casing 2 within which is pivoted for swinging movement a lever 3 carrying at one end a gate valve 4 normally open and adapted to be swung to closed position to cut off communication between the brake pipe and the air supply. Suitably fastened to the gate valve casing 2 is a motor comprising, in the present instance, a cylinder 5 in which is mounted for sliding movement a piston 6 having a piston rod 7 projecting into the casing 2 and connected through the medium of a pin and slot connection 8 with the upper end of the lever 3. Encircling the piston rod 7 is a coiled expansion spring 9 having one end abutting the end of the cylinder 5 connected with the valve casing and the opposite extremity in engagement with the confronting face of the piston 6, such spring serving to hold the piston 6 normally at its limit of outward movement within the cylinder 5 and the valve 4 in open position.

10 designates a governor comprising, in the present instance, a cylindrical casing 11

- equipped at one end with an outwardly projecting nipple 12 tapped onto the train line air pipe 1 at the side of the valve casting 2 opposite from the source of supply.
- 5 Formed in the casing 11 at a point above the nipple 12 is a valve seat 13 and normally engaging such seat is a valve plug 14. The upper end of the plug 14 is enlarged circumferentially to provide a head 10 15 capable of sliding movement within an annulus 16 disposed concentrically of the valve plug and secured to the inner side wall of the casing 11. By means of this construction, it will be seen that a fluid 15 tight joint is effected between the upper and lower portions of the governor casing so that when the valve is moved out of engagement with the seat 13 the air from the train line air pipe will pass into the lower 20 portion of the casing by way of the nipple 12 and remain below the valve plug. Formed on the plug circumferentially thereof adjacent to the seat engaging end is an annular flange 17 adapted to abut the lower 25 end of the annulus 16 in the upward movement of the valve plug thereby limiting the movement of the valve to open position. Threaded into the upper or outer end of the governor casing 11 is an adjusting nut 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955
- the casing 28 is a plug valve 29 formed with a longitudinal bore 30 alining axially with the passage through the pipe 27 and in open communication with such passage and having the rear end thereof closed. Formed in the outer surface of the valve 29 is an annular groove 31 communicating with the bore 30 in the plug by way of apertures 32. Formed in the casing 28 of the main valve is an inlet port 33 and tapped into such port is one extremity of a section of pipe 34, the opposite end of the pipe section being tapped onto the train line air pipe or brake pipe 1 at the side of the valve casing 2 opposite from the governor casing 11. Normally, the plug valve 29 is in open position, as illustrated in Fig. 1, so that the annular groove 31 in the outer wall thereof registers with the inlet port 33 in the casing thereby establishing communication between the air chamber 24 above the valve plug 14 and the train line air pipe between the valve casing 2 and the source of air supply, such air flowing from the train line air pipe through the pipe section 34, the inlet port 33, groove 31, apertures 32, bore 30, the passage in the pipe section 27, the coupling 26 and into the chamber 24. On the other hand, the air in the train line air pipe passes through the nipple 12 and engages the under surface of the valve 14 and tends to unseat such valve, but as the pressures on the upper and lower sides of the valve are equalized and balance each other the valve 14 remains seated under the action of gravity and the spring 22. Leading from the lower portion of the governor casing 11 above the valve seat 13 is an air conduit 35 having the outer extremity thereof connected with the outer end of the cylinder 5 of the motor controlling the gate valve 4.
- By means of this construction, it will be seen that as long as the main valve remains open as in Fig. 1 the governor valve 14 will be balanced whereby communication between the cylinder 5 and the train line air pipe will be cut off. On the contrary, when the main valve is actuated to closed position, as illustrated in Fig. 5, communication between the train line air pipe and the air chamber 24 is cut off, incident to the groove 31 in the main valve moving out of registration with the inlet port 33 in the casing 28. The pressure of the air in the chamber 24 is now reduced, incident to the air flowing into the atmosphere by way of the aperture 25 and, assuming the spring 22 to be exerting a pressure upon the upper end of the governor valve 14 less than the pressure in the train line, the valve 14 will be moved to open position under the pressure in the brake pipe immediately that the air pressure in the chamber 24 drops below the tension pressure exerted on the valve by the

restoring spring 22. For instance, if the brake system operates upon a fifteen pound reduction in the train line or brake pipe and the train line or brake pipe pressure is seventy pounds, the adjusting nut 18 will be manipulated to place the spring 22 under a tension to exert a pressure corresponding to fifty-five pounds on the upper end of the governor valve. Thus, when the pressure in the air chamber 24 is reduced, incident to the closing of the main valve, the governor valve is moved to open position against the spring under the action of the pressure in the train line air pipe. The air in the brake pipe now flows past the valve seat 13 and into the lower portion of the governor casing 11 and thence to the outer end of the cylinder 5 behind the piston 6 therein by way of the air conduit 35. As the air enters the cylinder 5 the piston 6 is moved against the action of the spring 9 thereby swinging the gate valve 4 across the passage of the air in the brake pipe so that communication between the brake pipe and the source of supply is cut off. Thus, recharging of the train line by the pumps or main air reservoir during a reduction is eliminated.

The cylinder 5 of the motor controlling the gate valve 4 is provided with a discharge aperture 36 adjacent to the outer end thereof and controlled by the piston 6 and designed to be uncovered by the piston as the latter approaches the limit of its inward movement, thereby placing the train line air pipe in communication with the atmosphere so that the air pressure will be reduced to that required to effect an application of the brakes. As soon as the air pressure in the brake pipe is reduced to the required extent, fifty-five pounds, in the present instance, the restoring spring 22, being set to exert a pressure of fifty-five pounds on the upper surface of the governor valve, re-acts to reseat the valve 14 thereby cutting off communication between the brake pipe and the cylinder and the brake pipe and the atmosphere.

In the embodiment of our invention selected for illustrative purposes, the main valve is electrically controlled and the end thereof confronting the adjacent extremity of the pipe 27 is equipped with a metallic disk 37 acting as an armature, while encircling the pipe 27 is an electro-magnet coil 38 adapted when energized to magnetize the pipe section 27 whereby the end of such pipe section within the casing 28 may act as a pole to attract the armature 37 and so slide the main valve to closed position, as in Fig. 5. Connected up with one of the wheels of the motor car or engine is a speedometer 39 and secured to the face or dial of the speedometer and adjustable thereover is a segmental strip 40 having one end connected

by way of a conductor 41 with one terminal of the magnet coil 38. The finger or needle of the speedometer is indicated at 42 and is adapted to engage the adjustable strip 40 when the speed of the train or car reaches 70 that to which the strip is adjusted and such finger or needle continues to engage the strip as long as the car or train continues to travel above the determined speed. The hand or needle 42 is electrically connected by way 75 of a conductor 43 with a brush 44 depending from the motor car or engine, while the free terminal of the magnet 38 is connected to a companion brush 45 by way of a conductor 46. 80

Located in advance of the entrance to each block and under the control of the signal blade of the semaphore of the road signal system controlling the entrance to such block are contact shoes 46 connected in circuit with a suitable source of electrical energy and a circuit closer under the influence of the adjacent signal blade. When the signal blade goes to caution position the circuit closer is actuated to closed position so that 85 when the brushes 44, 45 engage the shoes 46 a circuit will be completed with the effect to energize the magnet winding 38 in the event of the train passing the caution signal above the speed to which the strip 40 is adjusted. To illustrate, should the circuit closer, composed, in the present instance, of the needle 42 and the strip 40, be adjusted so that the needle 42 will engage the strip 40 when the speed of the train reaches thirty 90 miles an hour and should the train or motor car be traveling at thirty-five miles an hour when passing the contact shoes 46 under the control of a signal blade set at caution, the circuit will be closed, immediately that 95 the brushes 44, 45 engage the shoes 46 thereby energizing the magnet 38 and sliding the main valve to closed position whereby communication between the source of fluid supply and the brake pipe is cut off and the pressure in the brake pipe reduced to effect the operation of the brake equipment, as previously described. 100

It will be noted that the strip 40 and the needle 42 of the speedometer coact to produce an adjustable circuit closer and in this connection, we wish it to be understood that any form of circuit closer may be employed in conjunction with the speedometer to obtain the desired result. 115

Projecting into the outer end of the casing 28 of the main valve is one extremity of a metallic tube 47, while surrounding the portion of the tube beyond the casing of the main valve is a magnet coil 48 adapted when 120 energized to magnetize the tube 47, while secured to the adjacent end of the main plug valve is a metallic disk 49 acting as an armature and adapted to be attracted by the pole formed by the confronting ends of the 125

magnetized tube 47. This magnet coil 48 is of less strength than the coil 38 and is connected in an electric circuit 50 including a suitable source of electrical energy, as, for 5 instance, a battery 51. The terminals of the circuit 50 are connected to contact shoes 52, 52 projecting into the lower portion of the casing 11 of the governor below the valve 14 and insulated from said casing and from 10 each other and disposed in the path of movement of a disk 53 loosely surrounding the pin 54 carried by the lower extremity of a shank 55, the shank being passed into and secured to the valve plug 14 of the governor. 15 The lower end of the pin 54 is equipped with a head and interposed between the head and the under surface of the disk is a light expansion spring 56, while interposed between the upper surface of the disk and the shoulder formed at the junction of the pin 54 and the pin 55 is a similar expansion spring 57. In the normal position of the governor valve, that is, when such valve is in engagement with its seat, the disk 54 rests upon the 20 pins 52, 52 and so maintains the circuit of the magnet 48 closed thereby holding the latter energized and the main valve in open position. However, when the magnet coil 38 is energized to open the main valve, 25 such magnet coil overcomes the action of the coil 48 and slides the main valve to open position so that communication between the brake pipe and the air chamber 24 is cut off. Immediately succeeding the movement of 30 the main valve to closed position, the governor valve is opened under the action of the pressure in the brake pipe so that the circuit of the restoring magnet coil 48 is broken thereby permitting the main valve to remain 35 open succeeding the breaking of the circuit of the magnet coil 38, incident to the brushes 44, 45 leaving the contact shoes 46. It may be here stated that these contact shoes 46 are of such length as to insure the complete opening of the governor valve before 40 the circuit of the magnet 38 is broken.

When the governor valve reseats, incident to the pressure in the train pipe balancing that exerted by the restoring spring 32, as 45 previously described, the circuit of the restoring magnet coil 48 is closed and the main valve actuated to open position thereby permitting the gate valve 4 to reopen under the action of the spring 9 and the pressures in 50 the train pipe and the chamber 24 to be restored to normal.

Projecting into the lower portion of the governor casing 11 and disposed above the disk 53 are contact pins 58 identical in construction to the pins 52 and insulated from the casing and from each other. These contact pins are connected in series in a circuit 59 including the battery 51 and a suitable form of audible signal as a bell 60 and are 65 disposed at the limit of upward movement

of the disk so that when the governor valve is actuated to open position the circuit of the audible signal will be closed and the latter sounded whereby the engineer will be advised that the apparatus has been brought 70 into service.

The springs above and below the disk 53 act as shock absorbers and permit the pin carrying the disk to move relatively to the latter in the movement of the governor 75 valve. In this instance, the confronting portions of the pipe section 27 and the armature forming disk 37 on the main valve plug are constructed in such manner as to produce a ball joint connection between the pipe section and the valve plug when the main valve is actuated to closed position.

From the foregoing description taken in connection with the accompanying drawings, the construction, mode of operation 85 and manner of employing our invention will be readily apparent. It will be seen that we have provided a speed controlling apparatus for railway motor cars or trains whereby the speed of the car or train will be automatically cut down to the required limit in the event of the car attempting to pass a caution signal above the caution speed.

While we have herein shown and described one preferred form of our invention by way 95 of illustration, we wish it to be understood that we do not limit or confine ourselves to the precise details of construction herein described and delineated, as modification and variation may be made within the scope of 100 the claims without departing from the spirit of the invention.

We claim:

1. In speed controlling apparatus, the combination with the brake pipe of the air 105 brake system, of a valve controlling communication between said pipe and the source of air supply, a fluid motor for closing said valve, a connection between said motor and pipe, a balanced valve controlling said connection and normally closed, part of said connection being between one face of said last valve and said brake pipe, a connection between the remaining face of said valve and the source of air supply, a main valve 110 controlling said last connection and normally open whereby the pressures at both sides of said balanced valve will be equalized, means holding said main valve normally open, and means for actuating said 115 main valve to closed position against the action of said holding means whereby the pressure on the second-mentioned face of said balanced valve will be relieved and communication between the brake pipe and motor established to actuate said first valve to 120 cut off communication between the brake pipe and the source of supply.

2. In speed controlling apparatus, the combination with the brake pipe of the air 125

- brake system, of a valve controlling communication between said pipe and the source of air supply, a fluid motor for closing said valve, a connection between said motor and pipe, a balanced valve controlling said connection and normally closed, part of said connection being between one face of said last valve and said brake pipe, a connection between the remaining face of said valve and the source of air supply, a main valve controlling said last connection and normally open whereby the pressures at both sides of said balanced valve will be equalized, a normally energized electroresponsive device holding said main valve open, an electric circuit including said device, a circuit breaker in said circuit under the control of said balanced valve, an electroresponsive device for actuating said main valve to closed position against the action of said holding means whereby the pressure at the last-mentioned face of said balanced valve will be relieved and the valve actuated to establish communication between said motor and brake pipe and actuate said circuit breaker to deenergize the first-mentioned electroresponsive device, a signal, an electric circuit including said signal, and a circuit closer under the control of said balanced valve and adapted to close said signal circuit in the movement of the balanced valve succeeding the operation of the main valve.
3. In speed controlling apparatus, the combination with the brake pipe of the air brake system, of a valve controlling communication between said pipe and the source of air supply, a fluid motor for closing said valve, a connection between said motor and pipe, a balanced valve controlling said connection and normally closed, part of said connection being between one face of said last valve and said brake pipe, a connection between the remaining face of said valve and the source of air supply, a main valve controlling said last connection and normally open whereby the pressures at both sides of said balanced valve will be equalized, a normally energized electroresponsive device holding said main valve open, an electric circuit including said device, a circuit breaker in said circuit under the control of said balanced valve, and an electroresponsive device for actuating said main valve to closed position against the action of said holding means whereby the pressure at the last-mentioned face of said balanced valve will be relieved and the valve actuated to establish communication between said motor and brake pipe and actuate said circuit breaker to deenergize the first-mentioned electroresponsive device.
4. In speed controlling apparatus, the combination with the brake pipe of the air brake system, of a valve controlling communication between said pipe and the source of air supply, a fluid motor for closing said valve, a connection between said motor and pipe, a balanced valve controlling said connection and normally closed, part of said connection being between one face of said last valve and said brake pipe, a connection between the remaining face of said valve and the source of air supply, a main valve controlling said last connection and normally open whereby the pressures at both
- sides of said balanced valve will be equalized, a normally energized electroresponsive device holding said main valve open, an electric circuit including said device, a circuit breaker in said circuit under the control of said balanced valve, an electroresponsive device for actuating said main valve to closed position against the action of said holding means whereby the pressure at the last-mentioned face of said balanced valve will be relieved and the valve actuated to establish communication between said motor and brake pipe and actuate said circuit breaker to deenergize the first-mentioned electroresponsive device, a signal, an electric circuit including said signal, and a circuit closer under the control of said balanced valve and adapted to close said signal circuit in the movement of the balanced valve succeeding the operation of the main valve.
5. In speed controlling apparatus, the combination with the brake pipe of the air brake system, of a valve controlling communication between said pipe and the source of air supply, a fluid motor for closing said valve, a connection between said motor and pipe, a balanced valve controlling said connection and normally closed, part of said connection being between one face of said last valve and said brake pipe, a connection between the remaining face of said valve and the source of air supply, a main valve controlling said last connection and normally open whereby the pressures at both sides of said balanced valve will be equalized, a normally energized electroresponsive device holding said main valve open, an electroresponsive device adapted to actuate said main valve to closed position against the action of said normally energized device whereby the pressure at the last-mentioned face of said second valve will be relieved and the motor operated to cut off communication between said pipe and the source of supply, an electric circuit including said second-named electroresponsive device and normally open, and speed controlled means for closing said circuit when the car is traveling above a predetermined speed.
6. In speed controlling apparatus for motor cars, the combination with the brake pipe of the air brake system, of a valve controlling communication between said pipe and the source of supply, a fluid motor for closing said valve, a connection between said motor and pipe, a balanced valve controlling said connection and under the control of the brake pipe pressure and normally closed, a connection between the front face of said last valve and the train line air pipe at the reservoir side of said first valve, part of said first-named connection being between the rear face of said balanced valve and the train line air pipe at the remaining side of said first valve, a main valve controlling

5 said connection between the first valve face
10 of said second valve and the reservoir side
15 of said first valve and normally open, speed
20 controlled means for closing said main valve
25 whereby the pressure at the rear of said sec-
30 ond valve will be relieved and said motor
35 operated to cut off communication between
40 said pipe and the source of supply, and au-
45 tomatic means under the control of said bal-
50 anced valve for restoring said main valve
55 to normal position.

6. In speed controlling apparatus for motor cars, the combination with the brake pipe
15 of the air brake system, of a valve controlling communication between said pipe and
20 the source of supply, a fluid motor for closing said valve, a connection between said
25 motor and pipe, a balanced valve controlling said connection and under the control
30 of the brake pipe pressure and normally closed, a connection between the front face
35 of said last valve and the train line air pipe at the reservoir side of said first valve, part
40 of said first-named connection being between the rear face of said balanced valve and the
45 train line air pipe at the remaining side of said first valve, a main valve controlling
50 said connection between the front face of said second valve and the reservoir side of
55 said first valve and normally open, speed controlled means for closing said main valve
60 whereby the pressure at the rear of said second valve will be relieved and said motor
65 operated to cut off communication between
70 said pipe and the source of supply, automatic means under the control of said balanced
75 valve for restoring said main valve to normal position succeeding the pressure in the train line
80 pipe balancing that in said means.

7. In speed controlling apparatus for motor cars, the combination with the brake pipe
15 of the air brake system, of a valve controlling communication between said pipe and
20 the source of supply, a fluid motor for closing said valve, a connection between said
25 motor and pipe, a balanced valve controlling said connection and under the control
30 of the brake pipe pressure and normally closed, a connection between the front face
35 of said last valve and the train line air pipe at the reservoir side of said first valve, part
40 of said first-named connection being between the rear face of said balanced valve and the
45 train line air pipe at the remaining side of said first valve, a main valve controlling
50 said connection between the front face of said second valve and the reservoir side of
55 said first valve and normally open, speed controlled means for closing said main valve
60 whereby the pressure at the rear of said second valve will be relieved and said motor
65 operated to cut off communication between
70 said pipe and the source of supply, automatic means under the control of said balanced
75 valve for restoring said main valve to normal position succeeding the pressure in the train line
80 pipe balancing that in said means.

8. In speed controlling apparatus for motor cars, the combination with the brake pipe
15 of the air brake system, of a valve controlling communication between said pipe and
20 the source of supply, a fluid motor for closing said valve, a connection between said
25 motor and pipe, a balanced valve controlling said connection and under the control of the
30 brake pipe pressure and normally closed, a connection between the front face of said
35 last valve and the train line air pipe at the reservoir side of said first valve, part of said
40 first-named connection being between the rear face of said balanced valve and the
45 train line air pipe at the remaining side of said first valve, a main valve controlling
50 said connection between the front face of said second valve and the reservoir side of said
55 first valve and normally open, speed controlled means for closing said main valve
60 whereby the pressure at the rear of said second valve will be relieved and said motor
65 operated to cut off communication between
70 said pipe and the source of supply, said motor having a discharge port opening
75 into the atmosphere whereby the pressure in the brake pipe will be reduced
80 succeeding the operation of said motor, and an electroresponsive device for restoring
85 said main valve whereby the pressure at the rear of said second valve will be relieved
90 and said motor operated to cut off communication between said pipe and the source of supply,
95 said motor having a discharge port opening into the atmosphere whereby the pressure in
100 the brake pipe will be reduced succeeding the operation of said motor.

9. In speed controlling apparatus for motor cars, the combination with the brake pipe
15 of the air brake system, of a valve controlling communication between said pipe and
20 the source of supply, a fluid motor for closing said valve, a connection between said
25 motor and pipe, a balanced valve controlling said connection and under the control
30 of the brake pipe pressure and normally closed, a connection between the front face
35 of said last valve and the train line air pipe at the reservoir side of said first valve, part
40 of said first-named connection being between the rear face of said balanced valve and the
45 train line air pipe at the remaining side of said first valve, a main valve controlling
50 said connection between the front face of said second valve and the reservoir side of
55 said first valve and normally open, and an electroresponsive device for closing said
60 main valve whereby the pressure at the rear of said second valve will be relieved and said
65 motor operated to cut off communication between said pipe and the source of supply,
70 said motor having a discharge port opening into the atmosphere whereby the pressure in
75 the brake pipe will be reduced succeeding the operation of said motor.

10. In speed controlling apparatus for motor cars, the combination with the brake pipe
15 of the air brake system, of a valve controlling communication between said pipe and
20 the source of supply, a fluid motor for closing said valve, a connection between said
25 motor and pipe, a balanced valve controlling said connection and under the control
30 of the brake pipe pressure and normally closed, a connection between the front face
35 of said last valve and the train line air pipe at the reservoir side of said first valve, part
40 of said first-named connection being between the rear face of said balanced valve and the
45 train line air pipe at the remaining side of said first valve, a main valve controlling
50 said connection between the front face of said second valve and the reservoir side of said
55 first valve and normally open, an electroresponsive device for closing said main valve
60 whereby the pressure at the rear of said second valve will be relieved and said motor
65 operated to cut off communication between said pipe and the source of supply,
70 said motor having a discharge port opening into the atmosphere whereby the pressure in
75 the brake pipe will be reduced succeeding the operation of said motor, and an electroresponsive
80 device for restoring said main valve whereby the pressure at the rear of said second valve
85 will be relieved and said motor operated to cut off communication between said pipe and the source of supply,
90 said motor having a discharge port opening into the atmosphere whereby the pressure in
95 the brake pipe will be reduced succeeding the operation of said motor.

said main valve to normal position succeeding the pressures at both sides of said balanced valve equalizing.

11. In speed controlling apparatus for 5 motor cars, the combination with the brake pipe of the air brake system, of a valve controlling communication between said pipe and the source of air supply, a fluid motor for closing said valve, a connection between 10 said motor and pipe, a balanced valve controlling said connection and under the control of the brake pipe pressure and normally closed, a connection between the front face of said last valve and the train line air pipe of said last valve and the train line air pipe 15 at the reservoir side of said first valve, part of said first-named connection being between the rear face of said balanced valve and the train line air pipe at the remaining side of said first valve, a main valve controlling said connection between the front face of said second valve and the reservoir side of said first valve and normally open, an electroresponsive device for closing said main valve whereby the pressure at the rear of 20 said second valve will be relieved and said motor operated to cut off communication between said pipe and the source of supply, said motor having a discharge port opening into the atmosphere whereby the pressure in 25 the brake pipe will be reduced succeeding the operation of said motor, an electroresponsive device for restoring said main valve to normal position succeeding the pressures at both sides of said balanced valve 30 equalizing, and means operable from said balanced valve in the movement thereof to closed position to energize said last electroresponsive device.

12. In speed controlling apparatus for 40 motor-cars, the combination with the brake pipe of the air brake system, of a valve

controlling communication between said pipe and the source of air supply, a fluid motor for closing said valve, a connection between said motor and pipe, a balanced valve 45 controlling said connection and under the control of the brake pipe pressure and normally closed, a connection between the front face of said last valve and the train line air pipe at the reservoir side of said first valve, 50 part of said first-named connection being between the rear face of said balanced valve and the train line air pipe at the remaining side of said first valve, a main valve controlling said connection between the front face of said second valve and the reservoir side of said first valve and normally open, an electroresponsive device for closing said main valve whereby the pressure at the rear of 55 said second valve will be relieved and said motor operated to cut off communication between said pipe and the source of supply, said motor having a discharge port opening into the atmosphere whereby the pressure in the brake pipe will 60 be reduced succeeding the operation of said motor, an electroresponsive device for restoring said main valve to normal position succeeding the pressures at both sides of said balanced valve equalizing, and a speed 65 controlled circuit closer controlling the energization of said first electroresponsive device and adapted to close the circuit thereof at a predetermined speed.

In testimony whereof we affix our signatures in presence of two witnesses.

LLEWELLYN E. JONES.

JOHN W. BREAKY.
